UNITED STATES PATENT OFFICE.

JAMES MARSDEN, OF WIGAN, ENGLAND.

DESIGN FOR A PATTERN-CHART.

SPECIFICATION forming part of Design No. 29,601, dated November 1, 1898.

Application filed September 21, 1898. Serial No. 691,566. Term of patent 14 years.

To all whom it may concern:

Be it known that I, JAMES MARSDEN, a subject of the Queen of Great Britain, residing in Wigan, in the county of Lancaster, England, have invented and produced a new and original Design for a Pattern-Chart, of which the following is a specification, reference being had to the accompanying drawing, forming a part thereof.

5 The drawing is a plan view of a pattern-chart, showing my new design.

As shown in the drawing, the leading or material feature of my design consists of a pattern-chart having represented thereon the 15 novel arrangement of patterns for ties, as now described.

Upon the pattern-chart is shown a number of ties A A A, having reduced central portions, the ties being arranged longitudinally side by side upon the pattern-chart. 20

Having thus described my invention, what I claim as new therein, and desire to secure by Design Letters Patent, is—

The design for a pattern-chart substantially as herein shown and described. 25

In witness whereof I have hereunto signed my name, this 5th day of September, 1898, in the presence of two subscribing witnesses.

JAMES MARSDEN.

Witnesses:

ROBERT KAY CROOK,
CHARLES SPARY.
